CLAIM

The ornamental design for a truck box rack for cab protection and long cargo, shown and described.

DESCRIPTION

FIG. 1 is a perspective view of the truck box rack and cab protector;

FIG. 2 is a rear elevational view of the front truck box rack and cab protector;

FIG. 3 is a top plan view of the front truck box rack and cab protector;

FIG. 4 is a bottom plan view of the front truck box rack and cab protector; and,

FIG. 5 is a side elevational view of the front truck box rack and cab protector.

The broken line showing of environment is for illustrative purposes only and forms no part of the claimed design.

The rack is shown on an enlarged scale in FIGS. 2-5 as compared to FIG. 1.
